UNITED STATES PATENT OFFICE.

BENJAMIN E. D. STAFFORD AND ETHAN I. DODDS, OF PITTSBURGH, PENNSYLVANIA,
ASSIGNORS TO FLANNERY BOLT COMPANY, OF PITTSBURGH, PENNSYLVANIA.

STAYBOLT STRUCTURE.

1,359,628.

Specification of Letters Patent. Patented Nov. 23, 1920.

Application filed September 12, 1919. Serial No. 323,363.

To all whom it may concern:

Be it known that we, BENJAMIN E. D. STAFFORD and ETHAN I. DODDS, citizens of the United States, and residents of Pittsburgh, in the county of Allegheny and State of Pennsylvania, have invented certain new and useful Improvements in Staybolt Structures; and we do hereby declare the following to be a full, clear, and exact description 10 of the invention, such as will enable others skilled in the art to which it appertains to make and use the same.

This invention relates to improvements in staybolt structures for boilers,—one object 15 of the invention being to provide a mounting for the headed end of the staybolt at the outer boiler sheet, which shall be universally adjustable to insure accurate alinement of the staybolt with its points of connection 20 with the respective boiler sheets, and which shall be adaptable for staybolts having heads which are smaller than the heads of a majority of the staybolts used in some boilers.

With this and other objects in view, the 25 invention consists in certain novel features of construction and combinations of parts as hereinafter set forth and pointed out in the claim.

The accompanying drawing is a sectional 30 view showing an embodiment of our invention.

1 represents an outer boiler sheet and 2 the inner sheet of a boiler. The outer boiler 35 sheet is provided with an opening 3, a portion of the wall of which is curved or rounded transversely of the sheet, to afford a rounded seat 4 on which a bearing sleeve or member 5 has a universally movable or 40 adjustable mounting. The outer end portion of the bearing sleeve may be made substantially cylindrical in form but its inner end portion which enters the opening in the boiler sheet is rounded, presenting an outer 45 rounded face 6 mounted on the rounded wall 4 of said opening, and an interior rounded seat 7.

A staybolt 8 is secured in any suitable manner to the inner boiler sheet 2 and at its 50 outer end said bolt is provided with a head 9 disposed within the bearing sleeve.

In the drawing, the staybolt is shown having a head which is appreciably smaller than the majority of staybolts used in some

types of boilers, but it sometimes happens 55 that it is desirable to employ bolts having small heads and in order that such bolt heads may be mounted in universally movable or adjustable bearing sleeves of what might be termed "standard size," we employ 60 a supplemental bearing member 10 which will compensate for the difference in size between the small bolt head and a bolt head of a larger size for which the bearing sleeve may be adapted. 65

The supplemental bearing member is made in the form of a tapering inner sleeve disposed between the seat 7 in the sleeve and the bolt head and having an outer curved face which is freely movable on the seat 7 70 and a curved or rounded inner seat 11 for the rounded head of the staybolt.

It will be understood that supplemental bearing members of different thicknesses 75 may be provided and made interchangeable to accommodate the particular size of bolt head which may be employed.

After the bearing sleeve 5 shall have been properly adjusted to insure accurate alinement of the staybolt with its points of connection 80 with the respective boiler sheets, said sleeve will be intimately united to the boiler sheet by means of a weld 12.

The bearing sleeve or member 5 is threaded 85 interiorly and receives a threaded hollow plug or closure 12 having an angular portion 13 to receive a wrench. Between the inner end of the plug or closure 12 and a shoulder 14 in the bearing sleeve, a gasket 15 may be disposed. 90

Having fully described our invention, what we claim as new and desire to secure by Letters-Patent, is:—

In a staybolt structure, the combination 95 with a boiler sheet having an opening, of a bearing member having initial universally movable mounting, a staybolt having a head located in said bearing member, a freely movable member disposed between the bolt head and said bearing member, and a weld 100 uniting said universally movable bearing member to the boiler sheet.

In testimony whereof, we have signed this specification.

BENJAMIN E. D. STAFFORD.
ETHAN I. DODDS.

Witness:

EDWIN S. RYCE.
